UNITED STATES PATENT OFFICE.

JOHN E. WOOLEY, OF FINDLAY, NEW YORK.

OUTLET-VALVE FOR OIL-TANKS.

1,155,537.

Specification of Letters Patent.

Patented Oct. 5, 1915.

Application filed January 4, 1915. Serial No. 513.

To all whom it may concern:

Be it known that I, JOHN E. WOOLEY, a citizen of the United States, residing at Findlay, in the county of Hancock and State of Ohio, have invented a new and useful ⁵ Outlet-Valve for Oil-Tanks, of which the following is a specification.

The present invention relates to improvements in outlet valves for oil tanks, or for ¹⁰ tank cars of other types, wherein it is desirable to dispose the valve within the tank to drain the contents thereof, one object of the invention being the provision of a simple construction of valve, the casing of which ¹⁵ is adapted to be threaded from above into the upper end of the outlet pipe of the tank and carry a frusto-conical valve member resiliently held seated in place, the upper end of the casing being open for ready access to the valve while the sides of the casing ²⁰ are provided with diametrically disposed ports for registration with the diametrically disposed ports of the frusto-conical hollow valve, which is opened through the lower end for directing the fluid into the outlet pipe.

A further object of the present invention, ²⁵ is the provision of a valve of this character, which is simple, inexpensive and durable in construction and which is therefore thoroughly practical and useful.

With the foregoing and other objects in view which will appear as the description proceeds, the invention resides in the combination and arrangement of parts and in the details of construction hereinafter described and claimed, it being understood that changes in the precise embodiment of the invention herein disclosed can be made ³⁵ within the scope of what is claimed without departing from the spirit of the invention.

In the drawings—Figure 1 is a vertical central sectional view through the lower portion of an oil tank and the upper portion of ⁴⁰ an outlet pipe thereof, with the present valve in operable relation thereto, the said valve being shown in section. Fig. 2 is a side elevation of the complete valve and valve casing *per se*. Fig. 3 is a top plan view thereof.

Referring to the drawings, the numeral 1 ⁴⁵ designates the tank which is provided with the outlet pipe 2, the upper end of which is provided with the interiorly screw threaded portion 3 for the reception of the exterior threads 4 of the lower tapered end of the

valve casing 5. The valve casing 5 is disposed to fit within the tank in a vertical position and is provided with diametrically disposed ports 6, the lower edge of each of which is adjacent to the lower edge or bottom line of the tank. Mounted within the casing is the hollow frusto-conical valve 7, which is provided with the two ports 8 diametrically disposed in the walls thereof for registration with the ports 6 of the casing ⁶⁰ 5, so that the liquid within the tank may be directed through said ports and downwardly through the open end of the valve 7 and the casing into the outlet pipe 2. The upper end of the valve 7 is closed, and is provided with the concentrically disposed stem 9 which is provided with the centrally disposed angular or square socket 10, the purpose of which will presently appear. Surrounding the stem 9 and exerting a pressure downwardly to hold the valve 7 seated properly ⁶⁵ within the tapered portion of the casing 5, is a spring 11, the upper end of which is held in proper position by means of the bridging plate 12, whose terminals are ⁷⁰ clamped to the lugs 14 of the casing 5 as illustrated.

The bridging member 12 is provided with a circular opening 13, for the reception of the operating stem 15, which is provided ⁷⁵ with a squared end for the engagement with the opening or socket 10 of the stem 9 at one end, and with the handle 16 at the opposite end, said stem 15 being extended upwardly through the tank interiorly thereof, so that ⁸⁰ the handle 16 may be operated to open and close the valve 7.

From the foregoing description, it is evident that with the present construction of the valve, the member 5 is merely to be ⁸⁵ oscillated or rotated one-quarter revolution to place the ports thereof in registration with the ports of the casing, and that the liquid is directed through the ports interiorly of the valve and valve casing into ⁹⁰ the upper end of the outlet pipe, the upper end of the valve being sealed, so that the spring will hold the same downwardly and thus prevent the leakage of the fluid or liquid through the upper open end of the valve ⁹⁵ casing into the outlet pipe 2.

By this construction of valve, the member ¹⁰⁰ 5 is rotated in the same plane and the amount of fluid is regulated entirely by the coöperation of the ports of the casing and ¹⁰⁵ 110

valve requiring merely a quarter turn to place the ports in full registration or out of registration.

It is also apparent that by reason of the 5 bridging member 12 and its proper connection with the casing, that the spring 11 will be held in place to exert the proper pressure to maintain the frusto-conical valve member 7 properly seated in a tight condition and yet so that the same may be properly oscillated.

By threading the upper inlet end of the outlet pipe 2, the present valve may be properly assembled before introduction therein 15 as it is merely necessary to utilize the lugs 14 to rotate the casing to cause the threaded portions 3 and 4 to properly engage.

What is claimed is:

1. The combination with a liquid tank, 20 and an outlet pipe therefor having an interiorly threaded portion of slightly greater diameter than the inlet of the pipe, of a valve for controlling the pipe, including a casing having a frusto-conical lower end, 25 said end being exteriorly threaded for engagement with the threads of the outlet pipe, a frusto-conical valve having a socket formed therein from the lower reduced end thereof and provided with diametrically 30 disposed ports, said casing in the frusto-conical portion thereof being provided with diametrically disposed ports for registration with the ports of the valve, a stem carried by the frusto-conical valve and extending in 35 an opposite direction to the socket thereof, a spring surrounding said stem, a bridging member connected across the valve casing and exerting a pressure upon the spring to hold the valve seated within the casing, and 40 means for operating the valve extending

through the bridging member and engaging the stem.

2. The combination with a liquid tank, and an outlet pipe therefor having an interiorly threaded portion of slightly greater 45 diameter than the inlet of the pipe, of a valve for controlling the pipe, including a casing having a frusto-conical lower end, said end being exteriorly threaded for engagement with the threads of the outlet 50 pipe, a frusto-conical valve having a socket formed therein from the lower reduced end thereof and provided with diametrically disposed ports, said casing in the frusto-conical portion thereof being provided with 55 diametrically disposed ports for registration with the ports of the valve, a stem carried by the frusto-conical valve and extending in an opposite direction to the socket thereof, a spring surrounding said stem, a bridging 60 member connected across the valve casing and exerting a pressure upon the spring to hold the valve seated within the casing, the said stem being provided with an angular socket in the upper end thereof and said 65 bridging member being provided with a circular opening concentric to the socket, and an operating stem having an end seatable within the angular socket of the valve stem and extending through the circular opening 70 of the bridge, whereby the valve may be oscillated.

In testimony that I claim the foregoing as my own, I have hereto affixed my signature in the presence of two witnesses.

JOHN E. WOOLEY.

LAURA ROTH,
FRANK H. HUFFMAN.

Copies of this patent may be obtained for five cents each, by addressing the "Commissioner of Patents, Washington, D. C."

It is hereby certified that the residence of the patentee in Letters Patent No. 1,155,537, granted October 5, 1915, upon the application of John E. Wooley, for an improvement in "Outlet-Valves for Oil-Tanks," was erroneously given as "Findlay, New York," whereas said residence should appear as *Findlay, Ohio*; and that the said Letters Patent should be read with this correction therein that the same may conform to the record of the case in the Patent Office.

Signed and sealed this 23rd day of November, A. D., 1915.

[SEAL.]

J. T. NEWTON,

Acting Commissioner of Patents.
